UNITED STATES PATENT OFFICE.

JULIUS I. LIVINGSTON AND WILLIAM GRISCOM, JR., OF BOUND BROOK,
NEW JERSEY, ASSIGNEES TO THE STANDARD PAINT COMPANY, OF
NEW YORK.

PLASTIC COMPOUND FOR ROOFING, &c.

SPECIFICATION forming part of Letters Patent No. 416,791, dated December 10, 1889.

Application filed April 3, 1889. Serial No. 305,827. (No specimens.)

To all whom it may concern:

Be it known that we, JULIUS I. LIVINGSTON and WILLIAM GRISCOM, Jr., citizens of the United States of America, residing at Bound Brook, county of Somerset, State of New Jersey, have invented certain new and useful Improvements in Plastic Compounds for Roofing, &c.; and we do declare the following to be a full, clear, and exact description of the invention, such as will enable others skilled in the art to which it appertains to make and use the same.

Our invention relates to improvements in plastics, and has for its prime object the production of a compound for roofing and analogous purposes, which shall possess great fire-proof qualities and a very low degree of sensitiveness to heat. It may be used directly upon a suitable sheathing or foundation, or may be applied to a suitable base or sheet of textile or fibrous material and used in the ordinary way as roofing fabric.

The invention consists, essentially, in combining infusorial earth with maltha. The infusorial earth, admixed with the material named, gives to it the quality of resisting the action of heat and renders it substantially fire-proof. It also renders a roofing or coating less brittle in cold weather, as softer maltha can be used without being influenced by heat. It will be appreciated, therefore, that the infusorial earth adds important qualities to the compound to which it is added, since the uses of such compound expose them to the very conditions against which the infusorial earth is calculated to defend. The infusorial earth, mixed in proper proportions with the maltha, will prevent the compound from growing soft and running when exposed to the sun's rays in hot weather, and will prevent the material from becoming brittle and cracking in cold weather, for the reason that softer material can be used when mixed with the infusorial earth without being influenced by heat. The presence of the infusorial earth also prevents sparks from locomotives, &c., from igniting or having any influence upon the compound.

In a patent granted to Truman J. Pearce

and Melvin W. Beardsley, on the 14th day of September, 1886, No. 348,996, a roofing fabric was described and claimed, which consisted of maltha and a basis or foundation of fibrous or textile material, and two processes of applying the maltha to the basis are described— viz., the hot, by reducing the maltha to a viscid or fluid condition; and the cold, by mixing a solvent—such as bisulphide of carbon—with the maltha. The maltha mentioned in that patent is the same maltha which we use and with which infusorial earth is to be mixed, and the present invention, therefore, contemplates an improvement upon the patent named. The infusorial earth adds its heat-resisting qualities to the maltha, and also prevents its cracking in low temperature for the reasons already stated.

In intermixing the infusorial earth with the maltha we employ the hot process, and heat the maltha or other carbon to perfect fusion, when the earth is mingled with it, and also bring it to a proper temperature when the mixture is to be applied to the roof or to the basis of the roofing fabric.

The proportion of infusorial earth to be used depends upon the hardness desired for different purposes and in different climates. To increase the hardness and density of the compound the percentage of the infusorial earth is increased, which will produce a compound more applicable for roofing direct upon a foundation or sheathing, and also for tropical and very mild climates, while for more severe climates and for the production of roofing fabric a less percentage of the infusorial earth need be used.

We have found that for the climate of New York city a compound of about the following proportions is suitable: Soft maltha, twenty-four ounces, avoirdupois weight; infusorial earth, eight ounces, avoirdupois weight. The proportions will also depend upon the natural condition of the maltha, the hardness of which varies in different situations and conditions, and also upon the density of the infusorial earth, which differs widely in various samples. We do not, therefore, desire to limit ourselves to any definite proportions, as it is

evident that they may be varied within wide limits, according to the requirements of the case and the conditions of the ingredients of the compound, without departing from the spirit or sacrificing the advantages of our invention.

Having thus described our invention, what we claim, and desire to secure by Letters Patent, is—

10 A roofing compound consisting of a com-

bination of maltha and infusorial earth, substantially as herein set forth.

In testimony whereof we affix our signatures in presence of two witnesses.

JULIUS I. LIVINGSTON.
WILLIAM GRISCOM, JR.
